(57) **CLAIM**

The ornamental design for a solar roadway panel, as shown and described.

DESCRIPTION

FIG. 1 is a perspective view of a solar roadway panel showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a cross-sectional view thereof, taken along line 8-8 of FIG. 2; and,

FIG. 9 is a front elevation view thereof, shown in environmental use.

The broken lines shown represent unclaimed subject matter and form no part of the claimed design.
